UNITED STATES PATENT OFFICE.

MARY B. CHANDLER, OF CONCORD, NEW HAMPSHIRE.

INSTRUMENT FOR DRAFTING PATTERNS.

SPECIFICATION forming part of Letters Patent No. 270,983, dated January 23, 1883.

Application filed September 12, 1882. (No model.)

To all whom it may concern:

Be it known that I, MARY B. CHANDLER, a resident of Concord, in the county of Merrimack and State of New Hampshire, have invented certain new, useful, and Improved Instruments for Drafting Patterns; and I hereby declare the following to be a full and clear description thereof.

The object of my invention is to furnish the means whereby patterns may be produced for cutting out garments from measurements, (assuming the measurements to be correct,) which is at once adapted to either children or adults without "trying on" or "fitting," and which is also as simple as it is effectual.

My improved system is composed of but two pieces—viz., a swiveled combination-square and a curved pattern, the latter of which may be made of wood, metal, rubber, or any other suitable material, the form of which is very similar to the pattern ordinarily used by dress-makers and termed "arm-size."

My improved system will be clearly understood by reference to the accompanying drawings, of which Figure 1 represents a shield or curved pattern having one scale thereon divided by lines marked from 1 to 18, the figured lines being subdivided by shorter lines, which have no figures attached, said shorter lines being placed at equal distances between the figured lines, and also showing curved slots, which I use for different sizes of armholes. Fig. 2 shows one side of the swiveled combination rule or square as it appears when closed. Fig. 3 shows the opposite side of the swiveled combination rule or square, showing in dotted lines the arm or smaller half opened and swung around to a point nearly at a left angle with the large part of the rule.

The shield or piece A is cut out in such shape or form as that every curved line serves some purpose in drafting patterns by my improved system, and it may be provided with curved slots a^1 in and through its larger end, and conforming more or less in curvature to the line or edge a^2 , said curved slots a^1 and outer edge, a^2 , being required for drafting armholes.

The curved line forming the edge a^2 is used in drafting the "quarter-body," while the curved line forming the edge a^3 is used in drafting the

neck of garments. The scale on curve a^3 is so graduated that the exact distance between 1 and 2, 2 and 3, and so on, will be one-half inch, so that the total length of the scale from 1 to 18 is but nine inches, this scale being found of great advantage in obtaining the size of neck, and far preferable to the standard inch-scale.

There should be a small notch, a^4 , in the edge a^1 a^2 at or near the point indicated in Fig. 1, in order that the dress-maker may be guided in sewing sleeves into garments.

The combination rule or square is made in two parts, B B', said parts being united by a hinge, b, the long part B having thereon two scales divided into inches and fractions of inches, one scale on each side of rule. The parts B B' of the rule, to which the hinge b is riveted, are cut off on an angle of forty-five degrees, in order to permit the rule to form a square when opened as far as it will go.

There should be a mark, b' , upon the part B', struck on an angle of about sixty degrees, commencing at center of hinge b and terminating at outer edge of said part B', for the purpose of drafting the neck of garments. In use said mark b' is placed at a left angle with the part B, as shown in Fig. 3, by moving part B' by means of hinge b down far enough to square the mark b' with part B.

The curved end b^2 of piece B' is of great advantage in drafting the darts of a dress-waist, and is used when the rule or square displays the side which is shown in Fig. 3, the side which is shown in Fig. 2 being the side which comes in contact with the pattern while drafting the darts.

There may be a continuation of the curved end of the piece B' by beveling one side of the piece B, as shown in Fig. 2. The beveled side being placed down when drafting the darts, it will become necessary to incline the top of pencil out and away from the rule, which will cause the lead to follow the beveled edge of piece B.

The marks lettered B and D (shown on the side of square exposed to view in Fig. 2) are used in determining various measurements for back of waist and for darts, and I have not found them of use on the other side.

There will be a short scale on piece B', as

shown in Fig. 2, divided into fifteen equal parts, and figured consecutively from 18 to 43, inclusive, which will be marked "back waist."

On opposite side of square, as shown in Fig. 5 3, are two short scales, the one placed upon piece B being divided into twenty equal parts, and figured upon every other line consecutively from 15 to 35, inclusive, and marked "front neck."

10 The scale on piece B', being divided into eleven equal parts, and figured consecutively from 17 to 37, inclusive, is marked "back neck."

The inside of square B B' is used to obtain 15 the outlines for the back of waist, while the outside is used to draft the front of waist and the curved end of B' to draft darts, the piece A being formed of curves for drafting the armholes, or "arm-size," quarter-body, and 20 neck of waists

Having thus described my invention, I desire to claim—

1. In the piece A, the curved edge $a' a^2$, joined and forming one continuous line, as 25 shown in Fig. 1, and the curved edge a^3 , having thereon a scale divided by figures from 1 to

18, said curved edge $a' a^2$ being separated from edge a^3 by straight edges yy , all designed and arranged in a manner best calculated to produce the results hereinbefore described, in connection with the perforations or curved slots aa , forming part of arm-size pattern, as specified. 30

2. In the piece A, the combination of patterns comprising several sizes of armholes of 35 garments, the quarter-body, and neck-front, with a scale attached, as and for the purposes hereinbefore described and set forth.

3. The combination rule or square made in two parts, B B', and hinged at b, the short 40 rule B' having a radial line, b' , cut diagonally across it from a point directly in the center of the hinge b, the other end of which terminates in a curved line, (shown at b^2), provided with letters and scales divided by figures, as hereinbefore specified and described, and for the 45 purposes set forth.

MARY B. CHANDLER.
